UNITED STATES PATENT OFFICE.

WILLIAM WHARTON, JR., AND EDWARD SAMUEL, OF PHILADELPHIA, PENNSYLVANIA, ASSIGNEES TO WILLIAM WHARTON, JUNIOR, AND COMPANY, (INCORPORATED,) OF SAME PLACE.

DESIGN FOR A RAILWAY-RAIL.

SPECIFICATION forming part of Design No. 17,365, dated May 31, 1887.

Application filed April 26, 1887. Serial No. 236,256. Term of patent 14 years.

To all whom it may concern:

Be it known that we, WILLIAM WHARTON, Jr., and EDWARD SAMUEL, both citizens of the United States, and residents of Philadelphia, Pennsylvania, have invented a new and original Design for a Railway-Rail, of which the following is a specification.

Our design for a railway-rail is fully illustrated in the accompanying drawing, the view 10 in which is a transverse section showing the outline of the rail.

The rail has a head portion, A, connected to a depending web, B, on the inner side, and has a depending rib, a, on the outside. A 15 flange, D, projects from the depending inner web at an upward angle, forming a groove, e, between the outer end of the flange and the head A.

We claim—

The within-described design for a railway-rail, having in transverse section the outline illustrated, comprising the head A, having a rib, a, depending web B, and a flange, D, projecting at an upward angle from the web and forming a groove, e, substantially as shown 20 and described.

In testimony whereof we have signed our names to this specification in the presence of two subscribing witnesses.

WILLIAM WHARTON, JR.
EDWD. SAMUEL.
